(57) **CLAIM**

The ornamental design for a sink with insulated chamber, as shown and described.

DESCRIPTION

FIG. 1 is an elevated front perspective view of a sink with insulated chamber;

FIG. 2 is an elevated front perspective view of the sink with insulated chamber of FIG. 1 showing the new design in an illustrative use-case environment, including a lid for the insulated chamber;

FIG. 3 is a front elevation view of the sink with insulated chamber of FIG. 1, the opposite side being a mirror image thereof;

FIG. 4 is a left side elevation view of the sink with insulated chamber of FIG. 1;

FIG. 5 is a right side elevation view of the sink with insulated chamber of FIG. 1;

FIG. 6 is a top plan view of the sink with insulated chamber of FIG. 1; and,

FIG. 7 is a bottom plan view of the sink with insulated chamber of FIG. 1.

The dash-dash broken lines shown in the drawings illustrate unclaimed portions of the claimed design and form no part of the claimed design. The long dash-double short dash broken lines shown in the drawings illustrate unclaimed portions of the environment of the claimed design and form no part of the claimed design.
